US00D625308S

(12) **United States Design Patent**
Chen et al.

(10) **Patent No.:** **US D625,308 S**
(b4) **Date of Patent:** **** Oct. 12, 2010**

(54) **THIN CLIENT**

(75) Inventors: **Yun-Lung Chen**, Taipei Hsien (TW);
Hong-Jin Wu, Shenzhen (CN); **Qun Wang**, Shenzhen (CN)

(73) Assignee: **Hon Hai Precision Industry Co., Ltd.**,
Tu-Cheng, Taipei Hsien (TW)

(**) Term: **14 Years**

(21) Appl. No.: **29/341,262**

(22) Filed: **Aug. 3, 2009**

(51) **LOC (9) Cl.** **14-02**

(52) **U.S. Cl.** **D14/356**

(58) **Field of Classification Search** **D14/125, D14/137, 167, 168, 230, 231, 233, 235, 237, D14/240-242, 299, 432, 435, 436, 155, 496, D14/300-302, 313, 314, 214, 348-363, 365-370; D18/56; D10/65, 75, 78; D13/149, 162, D13/184, 199; D3/201, 273; 361/679.31-679.45**

(57) **CLAIM**

The ornamental design for a thin client, as shown and described.

DESCRIPTION

FIG. 1 is a perspective view of the thin client showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing of the various elements including the buttons, indicators, stand and input/output ports are for the purpose of illustrating unclaimed portions and form no part of the claimed design.

1 Claim, 7 Drawing Sheets
